Inventor

HORACE ST.JOHN de AULA DONISTHORPE

By his Attorney *Dr. J. Adams*

UNITED STATES PATENT OFFICE.

HORACE ST. JOHN de AULÀ DONISTHORPE, OF LONDON, ENGLAND, ASSIGNOR TO RADIO CORPORATION OF AMERICA, A CORPORATION OF DELAWARE.

THERMIONIC VALVE.

Application filed October 7, 1922, Serial No. 593,140, and in Great Britain October 24, 1921.

In a thermionic valve of the type wherein the cathode filament is surrounded wholly or partially by an anode which is open at its ends, the transfer of electrons from 5 cathode to anode has hitherto been attended by considerable wastage or non-utilization of the electrons near the open ends of the anode on account of the divergence of the paths of the electrons due to their mutual 10 repulsion.

The object of this invention is to prevent this wastage of electrons and thereby considerably to increase the efficiency of thermionic valves of the above mentioned type 15 and also to prevent the portions of the glass envelope of the valve which are opposite to the open ends of the anode from being bombarded. My invention is illustrated in the accompanying drawing, in which

20 Fig. 1 shows one form of my improved valve and

Fig. 2 shows a modification of my improved valve.

According to this invention I provide 25 means for energizing a helical grid 1 interposed between the anode 3 and the cathode 2 so that it will produce a magnetic field which will counteract the effect of mutual repulsion on the electrons emitted near the ends 30 of the cathode 2 and thereby hinder them from escaping through the open ends of the anode 3.

Two methods of arranging the helical grid so that it will fulfill the above mentioned 35 function will be described.

In the first method the grid 1 is wound uniformly in one direction and its two ends are connected to the positive terminal of the battery 4 while its middle point is connected 40 through a variable resistance 5 to the negative terminal of the said battery, so that each half will produce a magnetic field which will attract inwards the electrons at the extremities of the grid but these fields will neutralize one another at the middle of 45 the grid.

In the second method, the helical grid 1 is wound, one half in one direction and the other half in the opposite direction and the 50 ends of the grid are connected respectively

to the positive and negative terminals of a battery 4 through a variable resistance 5 so that magnetic fields are produced of a similar nature to those of the first method.

While I have described above a certain 55 theory for the operation of this invention, it is to be understood that I am not relying upon such theory, but that the same is offered merely to assist in the explanation of this invention.

Having now described my invention, I declare that what I claim is:

1. A thermionic valve comprising a cathode, an anode, and a double terminal helical grid interposed between said cathode 60 and said anode, said grid being constructed to produce a magnetic field of the same polarity at opposite ends thereof.

2. A thermionic valve comprising a cathode, an anode, and a double terminal 70 helical grid, said grid being adapted to be traversed by an electric current whereby to produce a magnetic field thereabout, and said helical grid being formed to produce said magnetic field with maximum intensity 75 at opposite ends thereof and with minimum intensity along a portion intermediate of the ends thereof.

3. A thermionic valve comprising a filamentary cathode, a grid helically wound 80 around said cathode, an anode surrounding said grid, terminals on opposite ends of said grid, and a single terminal connected to said grid intermediate of said first mentioned terminals, whereby said grid may be connected 85 to a source of E. M. F. to permit current to flow through separate portions of said grid and in opposite directions.

4. A thermionic valve comprising a cathode, an anode, and a double terminal 90 helical grid, said grid being divided into two portions at a point intermediate the ends thereof, a terminal carried by said grid at said point of division, and separate terminals on opposite ends of said grid, whereby said portions may be connected to a common source of E. M. F. in parallel relation to each other.

HORACE ST. JOHN de AULÀ DONISTHORPE.
